UNITED STATES PATENT OFFICE

2,425,815

REVERSIBLE GEARING

John N. Lavery, Long Beach, Calif.

Application March 16, 1944, Serial No. 526,731

2 Claims. (Cl. 74—377)

1

This invention relates to reversible gears of a generally similar nature to that constituting the subject matter of my United States Patent No. 1,257,253, issued February 19, 1918, upon which the present device constitutes an improvement.

The primary object of the invention is to provide, in a reversible gear of the aforementioned character comprising a constantly running drive shaft and a loosely mounted pulley, novel means for connecting said pulley to said drive shaft for actuation thereby in either direction.

Other objects of the invention are to provide a reversible gear of the character described which will be comparatively simple in construction, strong, durable, highly efficient and reliable in use, compact and which may be manufactured at low cost.

All of the foregoing, and still further objects and advantages of the invention, will become apparent from a study of the following specification, taken in connection with the accompanying drawings wherein like characters of reference designate corresponding parts throughout the several views, and wherein:

Figure 1 is a view in end elevation of a reversible gear constructed in accordance with the present invention, showing the drive shaft in cross section.

Figure 2 is a top plan view of the device.

Figure 3 is a view in vertical longitudinal section through the gear.

Figure 4 is a view in transverse section, taken substantially on the line 4—4 of Figure 2.

Figure 5 is a view in transverse section, taken substantially on the line 5—5 of Figure 3.

Figure 6 is a fragmentary view in section through the front portion of the device, showing the operating means for the clutch shoes.

Figure 7 is a view in transverse section, taken substantially on the line 7—7 of Figure 2.

Referring now to the drawings in detail, it will be seen that the embodiment of the present invention which has been illustrated comprises a stationary tube 1 which is to be firmly secured in any desired manner on a suitable support. On one end of the tube 1 is a stationary flange 2. Mounted on the flange 2 adjacent its periphery are stub shafts 3. Pinion gears 4 are journaled on the shafts 3.

Loosely mounted on the stationary tube 1 is a pulley which is designated generally by reference character 5. The pulley 5 includes a plate 6 which is journaled on the stationary tube 1, said plate carrying, on its periphery, a rim 7 which encircles the flange 2 and the pinion gears 4 thereon. The

2

pulley 5 is to have trained thereon an endless power transmission belt. Formed in the rim 7 of the pulley 5 is an integral ring gear 8 which is in mesh with the pinion gears 4.

5 A drive shaft 9, from any suitable source of supply, extends through the pulley 5 and has one end portion journaled in the tube 1. Rotatably mounted on the shaft 9, within the pulley 5, is a drum 10. The drum 10 is spaced concentrically from the rim 7 of the pulley 5. As best seen in Figure 3 of the drawings, the drum 10 includes a hub 11 which, in the embodiment shown, has mounted therein a bushing 12 and a bearing 13, said bearing being journaled on the shaft 9. A screw 14 secures the members 12 and 13 in position in the hub 11. A gear wheel 15 on one end portion of the hub 11 is engaged with the pinion gears 4. A grease retainer 16 is provided between the drum 10 and the gears 4, 8 and 15.

20 Fixed on the shaft 9 adjacent the drum 10 is a disc 17. Mounted on the disc 17, adjacent the periphery thereof, are pins 18 which project into the pulley 5. Friction clutch shoes 19 are operable radially on the pins 18 between the drum 10 and the rim 7 of the pulley 5. Radial slots 20 in the shoes 19 accommodate the pins 18.

25 Shafts 21 are journaled in the disc 17 at diametrically opposite points. Fixed on one end portion of the shafts 21 for operation between the ends of the shoes 19 are discs 22. Links 23 connect the shoes 19 to the discs 22 for actuation toward or away from each other thereby.

30 Mounted on the outer side of the disc 17 are 35 pairs of brackets 24. Pivotaly mounted between each pair of brackets 24 is a bell crank lever 25. Angular rods 26 operatively connect the bell crank levers 25, at one end, to arms 27 on the shafts 21.

35 A collar 28 is slidable on the shaft 9. Arms 29 are fixed on one end of the collar 28. The arms 29 are pivotally connected to the adjacent end portions of the bell crank levers 25. A ring 30 is rotatably mounted on the collar 28. An operating lever 31 for the collar 28 is operatively connected 45 to the ring 30.

40 It is thought that the operation of the device will be readily apparent from a consideration of the foregoing. Briefly, when the shoes 19 are out of contact with the drum 10 and the rim 7 of the pulley 5, the gear is in what may be considered neutral position. With the gear in neutral position, the pulley 5 is free of the shaft 9. To drive the pulley 5 in one direction, the collar 28 is shifted away from the disc 17 on the drive shaft 9, thus rotating the discs 22 in a direction to expand

the shoes 19 into engagement with the rim 7 of the pulley 5. It will accordingly be seen that a direct drive is had from the shaft 9 through the disc 17 and the shoes 19 to the pulley 5 for turning said pulley in the same direction as that in which said shaft is rotating. When it is desired to reverse the pulley 5 relative to the shaft 9, the collar 28 is shifted toward the disc 17 thereby contracting the shoes 19 and frictionally engaging said shoes with the drum 10. Thus, the drum 10 and the gear wheel 15 are connected to the shaft 9 for rotation with said shaft. The gear wheel 15 actuates the pinion gears 4 which, through the ring gear 8, drive the pulley 5 in the opposite direction.

It is believed that the many advantages of a reversible gear constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A device of the character described including a drive shaft, a fixed tube surrounding said shaft formed with an annular flange, stub shafts supported by said flange, gears on said shafts, a pulley having a hub loosely mounted on said tube, a ring gear on the inner surface of said pulley engageable with said gears a bearing collar journaled on said shaft, a bushing surrounding said collar, a hub secured to said bushing and collar supporting a clutch drum at one end and a gear at its opposite end engageable with the gears on the stub shafts, a plate secured to said drive shaft, radially adjustable clutch shoes supported on said plate, and a slidable operating means for selectively causing the frictional engagement of said clutch shoes with said drum and with said pulley for effecting the rotation of said pulley in either direction.

5 2. A device of the character described including a drive shaft, a fixed tube surrounding said shaft formed with an annular flange, stub shafts supported by said flange, gears on said shafts, a pulley having a hub loosely mounted on said tube, a ring gear on the inner surface of said pulley engageable with said gears, a bearing collar journaled on said shaft, a bushing surrounding said collar, a hub secured to said bushing and collar 10 supporting a clutch drum at one end and a gear at its opposite end engageable with the gears on the stub shafts, a plate secured to said drive shaft, radially adjustable clutch shoes supported on said plate, slidable operating means for selectively causing the frictional engagement of said clutch shoes with said drum and with said pulley for effecting the rotation of said pulley in either direction, and a grease retaining plate mounted on said last mentioned hub separating said drum 15 from said gearing.

JOHN N. LAVERY.
